Specification of Letters Patent.

Patented Aug. 13, 1918.

Application filed January 23, 1915. Serial No. 3,869.

To all whom it may concern:

Be it known that we, Professor GERARDUS JACOBUS VAN SWAAY, civil engineer, residing at Delft, Netherlands, and HENRI ISAÄC KEUS, electrical engineer, residing at Hengelo, Netherlands, formerly of Delft, Netherlands, subjects of the Queen of the Netherlands, have invented certain new and useful Devices for Transmitting Fluctuations in the Voltage or Current of an Alternating-Current System to Electroresponsive or Magnetically-Operated Devices, of which the following is a specification.

This invention relates to means with the aid of which fluctuations in the voltage or current in an alternating current system cause fluctuations in the operation of apparatus responding to the first mentioned fluctuations.

The object of the invention is to provide such means in which any fluctuations in the voltage or current of an alternating current system cause considerably stronger fluctuations in the operation of apparatus responding to the first mentioned fluctuations. With this means it is for instance possible to make electro-responsive magnetically operated, and other devices, adapted to be influenced or controlled by fluctuations in the voltage or current in an alternating current system, respond effectively to small fluctuations in said voltage or current to which such devices would otherwise not respond. The means according to the invention consists mainly of a transformer of well known construction, comprising a core having a plurality of legs with different magnetic resistances so arranged and connected that a magnetic flux induced in part of said legs can divide and pass through the remaining legs with different magnetic resistances, part of which first mentioned legs are provided with primary windings so proportioned and connected that under normal conditions part of said remaining legs are saturated with lines of force and the other part of said remaining legs are unsaturated. The primary windings of this transformer are, in accordance with the condition whether the means shall act on voltage or current fluctuations, connected either across or in the mains of the system. Fluctuations in the voltage or current respectively of the primary wind-

ings will have hardly any effect on the magnetic flux in the saturated circuit but will produce strong fluctuations in the magnetic flux in the normally unsaturated legs. This well known property is employed for realizing the object of the invention in a very simple and effective manner by arranging on the unsaturated legs of the core secondary windings and by connecting said secondary windings to the electro-responsive devices or by providing the attenuated legs of the core with air gaps and by arranging the magnetically operated devices so that they are under the influence of the attenuated leg in the air gap circuit.

The invention is further described with reference to the accompanying drawings in which the transformer for the sake of clearness is illustrated with three legs and in every instance provided with an air gap in the attenuated circuit. It should be understood, however, that the higher magnetic resistance in the unsaturated leg may be obtained by other means and that the core may comprise any suitable number of legs of which any suitable part may be so proportioned as to be normally saturated, while the remaining legs are unsaturated.

Figure 1 shows diagrammatically the transformer in combination with an electro-responsive device.

Fig. 2 is a modification of the arrangement according to Fig. 1.

Fig. 3 shows diagrammatically an arrangement in which the transformer is used in combination with an electro-responsive device for regulating or controlling the voltage of an alternating current generator.

Fig. 4 represents the transformer in combination with a secondary circuit in which the current should remain constant or should be regulated.

In these figures like characters indicate like parts.

Referring first to Fig. 1 the combination according to the invention comprises a transformer 2 comprising a core having three legs. These legs are so arranged that a magnetic flux induced in one of the legs can divide and pass through the remaining legs. In the transformer shown the magnetic flux is induced in the center leg 3 by means of alternating current traversing the primary

windings 4 arranged on this leg and connected across the mains 1 of an alternating electric circuit. The lines of force induced in the leg 3 divide through the legs 5 and 7. 5 These legs are so proportioned that the magnetic resistance is considerably greater in leg 7 than in leg 5 so that when leg 5 rises to saturation the magnetic flux in leg 7 is attenuated. In the example shown in the 10 drawings an air gap 6 is provided in this leg 7. To obtain the required effect this air gap will generally be longer than the air gap in the ordinary transformers, comprising a core of a similar construction. The primary 15 windings 4 are so proportioned that under normal conditions the magnetic flux induced by the current traversing them saturates the leg 5, so that for instance if the core is built up of soft iron laminations, the number of 20 lines of force directed through this leg amounts to over 10,000 per square centimeter. Fluctuations in the magnetic flux in the leg 3 will have hardly any effect on the flux in the leg 5. On the other hand such fluctuations 25 will produce disproportionately increased fluctuations in the leg 7. Any fluctuation in the ampere turns of the primary windings 4 therefore results in considerably stronger fluctuations in the magnetic induction 30 in the unsaturated leg 7, and if on this leg secondary windings are arranged the potential at the terminals of these windings will also be subject to considerable fluctuations. We have found that fluctuations of 35 say 10% in the number of ampere turns of the primary windings may be magnified to fluctuations of 100% in the potential induced in such secondary windings. It is obviously immaterial whether the fluctuations in the 40 number of ampere turns in the primary windings originate from variations in the number of turns or from fluctuations in the current. The latter may be due to variations in the voltage in an alternating electric circuit, when the primary windings are connected across the conductors as shown in the 45 drawings. The transformer may also be used for responding to fluctuations in the current in the conductors of the circuit by 50 connecting the primary windings in one of the conductors.

In the embodiment according to Fig. 1 this transformer is used in combination with secondary windings and an electro-responsive device. The secondary windings 8 arranged on the air gap leg, as and for the purpose described above, are connected to a coil 11 provided with a movable soft iron core 10. This core carries a mercury cup 9 in 55 such a manner that fluctuations in the force with which the core 10 is drawn into the coil 11 cause a reciprocating movement of the mercury cup 9. Thereby contacts 12 reaching into this cup will alternately get 60 out of contact with the mercury and be

plunged into the same so that the windings 13 are in part or wholly short circuited. The electro-responsive device is only shown diagrammatically and by way of example. A great number of other devices may be 70 used without departing from the spirit of the invention.

Fig. 2 for instance shows an embodiment in which the electro-responsive device for short circuiting the windings consists of a 75 coil 11 with movable core 10, which latter is attached to a balancing lever 14. One end of this lever is electrically connected to one of the terminals of windings 16 to be short circuited, while the other terminal of said 80 windings is connected to a contact 15. Oscillations set up in the lever 14 cause a periodic closing and opening of the circuit of the coil 16. The lever may make a large 85 number of oscillations.

A very useful embodiment of the invention is illustrated in Fig. 3. The arrangement shown is a combination of the transformer described above with a short circuiting relay of much the same construction as 90 the relay according to Fig. 2 and in which the circuit to be closed and opened contains the field regulator of the exciter of an alternating current generator. The arrangement is especially suited for controlling the voltage in an alternator. The primary windings 3 of the transformer are connected across two conductors leading from the alternator 23. The alternator illustrated in this figure is a three phase alternator; the 100 invention may, however, as well be applied to a single or two phase alternator. Instead of a coil 16 as in Fig. 2 the balancing lever and the contact control the field regulator 19 by periodically short circuiting same. 10 The balancing lever is very sensitive as in the well known Tirrill regulator. If now for some reason the voltage between the conductors, to which the primary windings 3 are connected drops the magnetic flux in the 11 unsaturated leg 7 will be weakened considerably with the result that the windings 11 release the core 10, whereupon the contact 15 is closed by the lever 14 and the field resistance of the exciter is short circuited. 11 The voltage of the alternator will increase with the rise in voltage of the exciter resulting from this short circuit. If the alternator voltage has attained the required value again the core 10 is drawn into the coil 11 12 thus causing the opening of the contact 15 by the lever 14 and switching the field regulator of the exciter into the circuit of its field windings. As stated above the lever 14 may be so constructed and balanced that it 13 may make a large number of oscillations per second. As will be clearly understood, however, the high degree of exactness at which the voltage of the alternator can be regulated or kept constant with this arrangement 14

is mainly due to the fact that the transformer magnifies very little fluctuations in the primary voltage to such an extent that they affect the relay 10, 11, 14, 15.

- 5 An embodiment of the invention with which the voltage or current in an alternating electric circuit can be controlled is illustrated in Fig. 4. Between the mains 19 of the circuit to be controlled and the mains 1 leading from the source of alternating current the transformer making part of the invention is connected. The primary windings 4 on the leg 3 of the core 2 are connected between the mains 1. The secondary 15 windings 18 are arranged on the saturated leg 5. Variations in the ampere turns of the primary windings will therefore cause relatively smaller fluctuations in the potential induced in the secondary windings 18. 20 In order to make the secondary circuit, however, independent of any fluctuations in the voltage on the primary side we arrange on the unsaturated leg 7 of the transformer windings 8, and connect them in series with 25 the windings 18 so that the electromotive force of the windings 8 reduce the electromotive force of the windings 18. In this manner the small fluctuations in the electromotive force of the windings 18 may be controlled to any extent; they may even be neutralized entirely as is clear from the following example. Assumed the primary voltage be 110 volts and the windings 18 so proportioned that under normal conditions 30 35 a voltage of say 140 volts will be induced in same. Assuming further that the voltage induced in the windings 8 amounts to 30 volts the resulting voltage between the mains 19 will be 110 volts. If now the primary voltage drops say 10% the voltage induced in the windings 18 will decrease to say 130 volts. If the windings 8 are suitably chosen the voltage of these windings will, however, fall to 20 volts so that the 40 45 resulting voltage between the mains 19 is still 110 volts. Instead of keeping the voltage constant the windings 8 may be so proportioned that the voltage is regulated to a required extent. The combination shown in 50 this embodiment is particularly suited to supply current to the voltage coils of alternating watt-hour meters, which are being calibrated.

The combination according to Fig. 4 is 55 also well adapted for large currents. In such case the arrangement may be used for

photometrical purposes or for feeding the lighting mains in factories in which the voltage on the mains is not constant.

The combinations according to this invention for operating relays have the advantage that small fluctuations in the voltage or current in the primary circuit will produce strong actions of the relays so that the latter will be made comparatively more sensitive 60 and will positively act upon small primary fluctuations. By these means no-load relays and minimum switches may be constructed to cut out at fluctuations in the primary circuit of 10 to 20 per cent.

70 Having now described our invention, what we claim as new and desire to secure by Letters Patent is:—

In an electric current system, an alternating current generator, a direct current exciting generator adapted to supply the magnet field coils of said alternating current generator with direct current, a transformer comprising a core having three legs of different magnetic resistances so arranged and 75 connected that a magnetic flux induced in one of said legs can divide and pass through the remaining legs with different magnetic resistances, a primary winding on said first mentioned leg so proportioned and connected 80 that under normal conditions one of said remaining legs is saturated with lines of force and the other of said remaining legs is unsaturated, conductors connecting said primary winding to the mains of said alternating current generator, a secondary winding arranged on said unsaturated leg only for producing a secondary electromotive 85 force, fluctuating disproportionately with fluctuations in the voltage impressed upon 90 said primary winding, conductors leading from said secondary winding, an electro-responsive device connected to said conductors, contacts adapted to be opened and closed in rapid succession by said electro-responsive 95 device, conductors leading from said contacts, and a field resistance of said exciting generator connected to said conductors and in the field windings of said exciting 100 generator.

105 In testimony whereof we affix our signatures in presence of two witnesses.
